UNITED STATES PATENT OFFICE

JAMES A. AMBLER, OF NATICK, MASSACHUSETTS.

METHOD OF FORMING BOOTS AND SHOES.

SPECIFICATION forming part of Letters Patent No. 239,304, dated March 29, 1881.

Application filed February 5, 1881. (No model.)

To all whom it may concern:

Be it known that I, JAMES A. AMBLER, of Natick, county of Middlesex, State of Massachusetts, have invented an Improvement in 5 Methods of Forming Boots and Shoes, of which the following description, in connection with the accompanying drawings, is a specification.

This invention relates to an improved method of closing the seams of boots and shoes and 10 other tubular articles, whereby the edges of the material and the final closing-seams which unite the said edges may be formed within the boot-leg or tubular article, to thus avoid subsequent turning, as now practiced, to conceal 15 the said edges and seams.

In the manufacture of boot-legs, one of the articles in connection with which this my 20 method is of especial value, it has been customary to close the side seams thereof with the front and back wrong side out, after which the boot-leg has been turned, at considerable expense, to bring the edges and seams within 25 the boot-leg. In the usual process the black faces of the front and back are placed together, the crimped front being then opened and somewhat flattened. Turning the closed leg inside 30 out to bring the black side of the leather outside necessitates folding the front at right angles to the length of the crease or crimp put into it on the crimping-form, the said fold rolling, as it were, from end to end of the boot-leg, 35 which action takes out a great part of the crimp given to the front on the crimping-form. The side seams of shoes are made in like manner, and also hydraulic hose.

In this my invention, if, for instance, it is desired to form a boot-leg, one of the side seams of the crimped front and back will first be closed in the usual manner, while the outer 40 or black faces of the material are in contact. This done the front and back are folded over in the opposite direction far enough to place the inner faces of the front and back together, after which the free edges of the front and back are turned in toward the center of the leg until the outer or black faces of the said edges touch together or rest upon the upper and lower sides of a welt, if one is used, as is preferred, and then the stitches to close the said 45 second seam and form the boot-leg into a tube are sewed through the said edges, or edges

and welt, thus turned into the tubular or cylindrical part of the boot-leg, as will be herein-after described. By my process the front, once brought into the desired form by crimping and 55 set, is not changed in shape, and the crimp once set is maintained in the front, instead of being partially lost by turning, and the front is left in the best possible shape for lasting.

Figure 1 represents, in cross-section, a boot-leg it as will appear with its first side seam sewed, the dotted lines showing the front and back folded over or turned back preparatory to having the second side seam closed. Fig. 2 is a similar section, showing the position of 60 the front and back while the second side seam is being sewed; and Fig. 3 is a side elevation of a boot-leg, the front being crimped.

In the drawings, *a* is intended to represent a crimped boot-front, and *b* the back thereof, 70 the heavier black lines representing the outer or black faces of the leather, and the thinner lines the inner or light-colored faces.

To form the first of the side seams of, say, a boot-leg, the black faces of the front and 75 back will be placed together, as in full lines, Fig. 1, with preferably a welt, *c*, between them near their side edges, and the same will be stitched together by a line of stitches, *d*, all as usual. The first seam to close one side of the 80 leg having been made, the front and back will be folded over or reversed, as in dotted lines, Fig. 1, and brought to the position, Fig. 2, where the free edges of the front and back are turned in far enough to bring their outer or black faces 85 together or against a second welt-strip, *e*, when the second side seam is closed by the stitches *f*, made through the said edges and welt, leaving the united edges 2 3 of the boot-leg within the tubular part thereof. This method avoids turning the boot-leg inside out, as heretofore necessary, after the last seam constituting the tubular part or boot-leg was finished with the edges 90 of the material and stitches outside.

In Fig. 3 the full line of the front shows the 95 outline given to it by the usual crimping-form, and by closing the final or last seam, which makes the boot-leg into a tube from the inside of the leg with the black side of the leather outward, I avoid any serious disturbance of the 100 crimped edge, such as would happen by turning the leg inside out after its side seams were

closed. The dotted lines, Fig. 3, are intended to show about the quantity of crimp lost in returning a boot-leg after fully closing it, the turned boot-leg losing the exact shape it had given to it by the form, or the shape it had before it was turned.

To enable me to form the second seam in the most expeditious manner, I have, in connection with A. C. and G. A. Ambler, invented a sewing-machine containing a horn or arm-like part, about which the boot-leg is folded, as will be described in the application to be filed for a patent for the said sewing-machine, the said horn or arm containing a hooked needle, cast off, and thread-guide, to make automatically the line of stitches *f*.

The seams of shoes, hose, and other tubular articles wherein the seams are to project inside, may be made in the manner herein described, and I do not desire to confine my claim to boot-legs, but desire by my method to unite other tubular articles which are difficult to turn right side out after having been fully closed wrong side out.

Referring to Fig. 2, the material of the back and front next the line of stitching *df* will be flattened down, rubbed, and finished in any usual way, so that the inwardly-turned edges of the material will not chafe the leg.

I claim—

1. That improvement in the art or method of closing that side or longitudinal seam of an article to bring it into and complete its tubular form to avoid subsequent turning thereof to bring the edges of the seam within the said article, which consists in bending or turning the free edges thereof within the said article, as shown and described, and then uniting the said edges within the said article while the material is right side out, substantially as herein described.

2. That improvement in the art or method of producing boot-legs which consists in the following steps, viz: first crimping the front and then closing the seams to unite the front and back, as described, the last side seam of the boot-leg, to bring it into tubular form, being made inside the leg with the front and back right side out, whereby subsequent turning of the boot-leg and loss of crimp in the front is avoided, substantially as described.

In testimony whereof I have signed my name to this specification in the presence of two subscribing witnesses.

JAMES A. AMBLER.
